OTHER PUBLICATIONS

Design U.S. Appl. No. 29/665,565, filed Oct. 4, 2018 Non Final Rejection dated Feb. 7, 2020, all pages.

Primary Examiner — Sandra S Snapp*Assistant Examiner* — Leisha N Price(74) *Attorney, Agent, or Firm* — Kilpatrick Townsend & Stockton LLP(57) **CLAIM**

The ornamental design for the fastener head, as shown and described.

DESCRIPTION

FIG. 1 is a perspective view of the first embodiment of a fastener head, showing the new design;

FIG. 2 is a side view thereof;

FIG. 3 is a top view thereof; and

FIG. 4 is a bottom view thereof.

FIG. 5 is a perspective view of the second embodiment of a fastener head, showing the new design;

FIG. 6 is a side view thereof;

FIG. 7 is a top view thereof; and,

FIG. 8 is a bottom view thereof.

The broken lines in the drawings illustrate portions of the fastener head that form no part of the claimed design.
